(57) **CLAIM**

We claim the ornamental design for a stapler, as shown and described.

DESCRIPTION

FIG. 1 is a perspective view of a stapler embodying the

present invention.

FIG. 2 is top view of the stapler.

FIG. 3 is a side view of the stapler.

FIG. 4 is a front view of the stapler; and,

FIG. 5 is a rear view of the stapler.

The portions of the stapler shown in broken lines are for illustrative purposes only and form no part of the claimed design. The side view opposite FIG. 3 is a mirror image of FIG. 3 and is not shown.
